CONCRETE BRICK PRESS

Hermen Kenneth Farris and Ward Renshaw,
Eldorado, Ill.

Application November 8, 1946, Serial No. 708,490

2 Claims. (Cl. 25—88)

1

Our invention relates to machine-tools and more particularly to brick presses.

The object of our invention is to provide a brick press adapted to receive concrete or the like from a material table, press the received material into the desired shape, move the mass a predetermined distance forward and sever a predetermined length from this mass to form a brick.

Another object of our invention is to provide a press of the type indicated above being equipped with a horizontally working plunger and a vertically working knife, the plunger and the knife being timed to cooperate, so that the knife is actuated to cut through the concrete or the like after the plunger has moved the mass forward the predetermined distance, and that the knife is returned into inoperative position, when the plunger starts again its forward movement against the mass of concrete delivered from the material table.

Other objects of our invention may appear in the following specification describing our invention with reference to the accompanying drawings illustrating a preferred embodiment of our invention.

It is however to be understood, that our invention is not to be limited or restricted to the exact construction and combination of parts described in the specification and shown in the drawings, but that such changes and modifications can be made, which fall within the scope of the claims appended hereto.

In the drawings

Figure 1 is an elevational side view, partly shown in section, of the brick making machine according to our invention.

Figure 2 is a top plan view of the machine shown in Figure 1.

Figure 3 is a vertical sectional view taken on line 3—3 in Figure 1 and illustrating the actuating mechanism of the dividing knife, and

Figure 4 is an elevational end view of the brick making machine showing the driving motor and the mechanism actuating the forwarding plunger.

Referring now in detail to the drawings the brick making machine forming the subject matter of our invention has a main bottom frame 10 made from angle iron and being substantially rectangular. Adjacent the front ends of the longitudinal side members of the main bottom frame 10 two uprights 11 are secured to said main bottom frame, and two rear uprights 12 are fastened to and extend upwardly from the rear ends of the longitudinal side members of

2

said bottom frame 10. A top frame 13 is supported on the top ends of the uprights 11 and 12.

On the front cross member of the main bottom frame 10 the base 14 of an electric motor 15 is 5 securely mounted. A V-groove pulley 16 is rigidly mounted on the shaft 17 of the motor 15.

A gear housing 18 is securely mounted on the front end of the top frame 13. A worm 19 is 10 rotatably supported by and extends longitudinally of said housing 18. The shaft 20 of the worm 19 extends beyond the forward wall of the gear housing 18 and a second V-groove pulley 21 is rigidly mounted on the forward end of the worm shaft 20, and is arranged directly above 15 the first mentioned V-groove pulley 16, so that a V-belt 22 can be trained over the two pulleys.

Under the worm 19 and meshing therewith a worm gear 23 is arranged inside the gear housing 18 and is rigidly mounted on a transversely extending shaft 24, which is rotatably supported by 20 bearings 25 formed in the side walls of the gear housing 18 and in two bearings 26 secured to the top frame 13.

The worm gear shaft 24 extends beyond the 25 outside bearing 26, and on each end of said worm gear shaft a lever arm 27 is rigidly mounted, to the free end of which an actuating lever arm 28 is 30 pivotally linked. The two rear ends of the actuating lever arms 28 are connected with each other by means of a rod 29 extending transversely over the longitudinal side members of the top frame 13.

A table 30 has a material supporting top 31 surrounded by upward extending walls 32. At 35 a distance below the table top 31 equal to the thickness of the bricks to be formed a bottom 33 is provided and is connected with the table top. The bottom 33 is resting on and secured to the top frame 13 and is firmly connected with the table top 31 by means of smooth longitudinal side walls forming a tunnel with the top and bottom.

A plunger 34 is slidably arranged inside this 40 tunnel and fits snugly therein. On the front of the plunger 34 two push bars 35 are formed or firmly fastened, extend forwardly therefrom and are pivotally connected with the transverse rod 29 between the actuating lever arms 28.

Adjacent the rear wall 32 on the table top 31 a 45 rectangular opening 36 is provided permitting a mass of material to be dropped from the table top 31 onto the bottom 33.

Back of the material table 30 an upright frame 50 37 is firmly mounted on the top frame 13 and on

each vertical side frame member a guide 38 is formed or rigidly fastened.

Coaxially with these guides two guide lugs 39 are arranged on the top frame 13 and two support rods 40 are slidably located in said guides 38 and guide lugs 39. A knife blade 41 extends between and is welded to the two support rods, so that its cutting edge faces downwardly and its forward side abuts the table top 31, the bottom 33 and the side walls connecting these two elements, when the knife blade 41 is located in its lowest position.

A helical spring 42 is attached with its upper end to the top transverse member of the upright frame 37 in the center thereof and with its lower end to an eye 43 formed in the center of the upper edge of the knife blade 41.

The two support rods 40 extend downwardly beyond the guide lugs 39 and are connected with each other on their lower ends by a stiffening rod 44.

On the underside of each longitudinal member of the top frame 13 a downwardly extending triangular bracket 45 is provided and on the lower end and on the inward side of each bracket 45 the apex portion of a bell crank lever 46 is pivotally mounted. One leg of each bell crank lever 46 extends substantially horizontally and rearwardly and is pivotally connected with an upwardly extending short lever 47, which is pivotally mounted on the stiffener rod 44.

The bell crank levers 46 and short levers 47 are arranged in the above described positions, when the knife blade 41 and the support rods 40 are in their lowest position. On top of the rear end of the rearwardly extending leg 48 of each bell crank lever 46 a coil spring 49 is securely mounted, and this leg 48 is bent, so that the coil spring 49 is located directly underneath the corresponding longitudinal member of the top frame 13.

The other leg 50 extends forwardly and downwardly when the first mentioned leg 48 is arranged horizontally, and the two legs 50 are connected with each other by a transverse bracket 51 pivotally attached to each leg 50 by a bolt 52 or the like selectively engaging one of a plurality of holes 53 arranged in the second legs 50.

Centrally of the bracket 51 a lug 54 having a hole therein is provided, and a pull rod 55 extends slidably through said hole and has on its outer end a thread 56 engaged by a nut 57 securing the rod 55 against forward movement, when arranged in adjusted position.

On the forward end of the pull rod 55 an elongated flattened bar element 58 is formed, which is provided in its under edge at a distance from its forward end with a notch 59.

On the rod 29, connecting the two actuating lever arms 28, a downwardly extending short lever 60 is mounted adjacent the longitudinal vertical center plane of the frame work of the brick press, and a pin 61 or the like is inserted in this lever 60, extends laterally therefrom and is adapted to engage the notch 59 in the flattened bar member 58.

A lift rod 62 is fastened to the under sides of the longitudinal side members of the top frame 13 and extends transversely of said frame, so that the flattened bar member is arranged above said lift rod 62.

A helical spring 63 is secured with one of its ends to the pull rod 55 adjacent the lug 54 on the transverse bracket 51, and with its other end

to an anchor rod 64 extending between the rear uprights 12.

Between the longitudinal side members of the top frame 13 a plurality of rollers 65 are rotatably arranged, so that a plate 66 can be positioned on said rollers 65 and extend underneath the bottom 33 of the material table 30.

When bricks are to be formed the machine is arranged as shown in Figure 1, that means the plunger 34 is arranged in partly retracted position, so that the hole 36 in the table top 34 is uncovered and material can be shoved through said opening onto the bottom 33 and into the table tunnel.

The pin 61 engages the notch 59 in the flattened bar member 58 pulling the pull rod 55 forwardly, whereby the two bell crank levers 46 are placed in the position shown in Figure 1, so that the rear legs 48 of said bell crank levers move the support rods 40 and the blade knife 41 into their low position as shown in Figure 1. The knife blade 41 closes the rear outlet of the table tunnel and the material placed in said tunnel cannot escape rearwardly therefrom.

When the motor 15 is then energized, the plunger 34, plunger arms 35 and the transverse bar 29 are moved further forwardly forcing the flattened bar member 58 to slide upwardly on the lift rod 62 until the notch 59 is lifted from the pin 61. The springs 63 and 42 will then move the support rods 40 and the blade knife 41 upwardly, so that the material in the table tunnel can be pushed rearwardly by the reciprocal movement of the plunger 34 and from the bottom 33 onto the plate 66, which rolls rearwardly on the rollers under the weight of the stone material. Continued movement of the plunger will bring the pin 61 again into engagement with the notch 59 in the flattened bar member 58, repeating the above described downward movement of the knife blade 41 to sever a predetermined portion of the brick material in the table tunnel ready for placement of the plate 66.

To prevent crumbling of the material during the movement thereof from the table bottom 33 onto the plate 66 the rear edge is beveled to incline downwardly and rearwardly, so that the formed brick material can slide smoothly and evenly from the table bottom onto the plate.

Having described our invention, we claim as new and desire to secure by Letters Patent:

1. In a brick press having motor-driven means, a reciprocable plunger of substantially rectangular cross-section driven thereby, a horizontally-disposed and substantially rectangular tunnel member in which the plunger is adapted to reciprocate, and a supporting frame for the tunnel member and the motor-driven means, the features including a substantially flat table forming the top of the tunnel member having an aperture for dropping material into said tunnel member in advance of said plunger, an upwardly-extending bounding wall upon the table forming a substantially rectangular open box therewith, a horizontally-disposed movable receiving plate located beneath the bottom portion of the tunnel member and having a group of supporting rollers arranged in a horizontal series upon said frame beneath said receiving plate and in the path of movement thereof, an upwardly-projecting frame rigidly disposed upon the end of the box remote from the motor-driven means, a pair of vertically-disposed rods guided upon the upwardly-projecting frame and the

supporting frame for vertical movement, a downwardly-directed knife fixed at the ends thereof upon intermediate portions of the vertically-disposed rods, means normally suspending said rods and said knife in position to dispose the knife at the delivery end of the tunnel member to form a stop for a brick being formed by the plunger in said tunnel member against said knife, and lever means connected to said rods beneath said knife and operated by the motor-driven means for moving the knife in said upwardly-extending frame to cut off the formed brick extruded from said tunnel member upon said receiving plate by said plunger.

2. In a brick press having motor-driven means, a reciprocable plunger of substantially rectangular cross-section driven thereby, a horizontally disposed and substantially rectangular tunnel member in which the plunger is adapted to reciprocate, and a supporting frame for the tunnel member and the motor-driven means, the features including a substantially flat table forming the top of the tunnel member being horizontally of greater extent in length and width than the latter and having an aperture for dropping material into said tunnel member in advance of said plunger, an upwardly-extending integral bounding wall upon the table forming a substantially rectangular open box therewith, a horizontally-disposed movable receiving plate located beneath the bottom portion of the tunnel member and having a group of supporting rollers arranged in a horizontal series upon said frame beneath said receiving plate and in the path of movement thereof, an upwardly-projecting frame rigidly disposed upon the end of the box remote from the motor-driven means, a pair of vertically-disposed rods guided upon the upwardly-

projecting frame and the supporting frame for vertical movement and being spaced apart to provide clearance for extrusion of bricks from the tunnel member, a downwardly-directed knife fixed at the ends thereof upon intermediate portions of the vertically-disposed rods, a spring connected to the knife and normally suspending it in position to dispose said knife at the delivery end of the tunnel member to form a stop for a brick being formed by the plunger in said tunnel member against said knife, a bell crank lever pivoted on the supporting frame below said box and tunnel member, a link operated by said motor-driven means and connected to one end of the bell crank lever, a second link connected to the other end of the latter lever, a cross-bar connected at the ends thereof to the lower ends of the vertically-disposed rods and at an intermediate portion to said second link for moving the knife in said upwardly-extending frame to cut off the formed brick extruded from said tunnel member upon said receiving plate by said plunger.
